UNITED STATES PATENT OFFICE.

JAMES POWERS, OF NEW YORK, N. Y., ASSIGNOR TO POWERS ACCOUNTING MACHINE COMPANY, OF NEW YORK, N. Y., A CORPORATION OF DELAWARE.

ELECTRICAL CARD-TABULATING MACHINE.

1,245,505.

Specification of Letters Patent. Patented Nov. 6, 1917.

Application filed August 21, 1915. Serial No. 46,704.

To all whom it may concern:

Be it known that I, JAMES POWERS, a citizen of the United States, residing in New York, in the county of New York and State of New York, have invented certain new and useful Improvements in Electrical Card-Tabulating Machines, of which the following is a specification.

This invention relates to accounting machines coöperating with record cards.

One of the main objects of the present invention is to provide electrical connecting means whereby the tabulating mechanism is actuated by the analyzing mechanism.

15 A particular feature of the invention is the provision of a contact for each row of pins adapted to be engaged a number of times corresponding to the character of the pin analyzed, which engagement of said contact will in turn release a sector corresponding to such row of pins one notch every time said contact is engaged so that the sector will be advanced a number of notches equal to the number of times the 20 contact of said analyzing mechanism is engaged.

Another feature of the invention is the means for disconnecting the releasing mechanism for sectors so as to prevent the actuation of the same when restoring the analyzing mechanism.

Still another feature of the invention is the means for clearing the machine whenever an erroneous record has been made.

35 A still further feature of the invention is the means for interrupting the operation of the machine whenever an erroneous record has been made, whereupon such record may be manually reset and then the operation of the machine resumed.

40 These and other features, capabilities and advantages of the invention will appear from the detail description of one specific embodiment thereof illustrated in the accompanying drawings, in which—

Figure 1 is a front end elevation of the complete machine.

Fig. 2 is a plan view of the same.

Fig. 3 is a view, partly in section, showing 50 the rows of racks of the analyzing mechanism and the rows of racks of the tabulating mechanism.

Fig. 4 is a side elevation, partly in section, showing the pin-box and related parts of the analyzing mechanism and the rack-actuating means of the tabulating mechanism.

Fig. 5 is a section showing a fragmental front end view of the tabulating mechanism.

Fig. 6 is a fragmental plan view of the manually operated tabulating mechanism shown in Fig. 5.

Fig. 7 is a diagrammatic view showing the several contacts and the thereto-connected wiring of both the analyzing and tabulating mechanisms.

Fig. 8 is a fragmental perspective showing the contacts out of engagement with the racks of the analyzing mechanism.

Fig. 9 is a perspective of one of the racks of the analyzing mechanism.

Fig. 10 is an enlarged fragmental view, partly in section, illustrating the relative positions of a rack of the analyzing mechanism and its contact when such rack is stopped by a pin.

Fig. 11 is a fragmental perspective showing the racks of the machine-operated tabulating mechanism and the actuating means therefor.

Fig. 12 is a perspective view of one of the racks of the machine-operated tabulating mechanism.

Figs. 13, 14 and 15 are fragmental views of pins for the tabulating mechanism showing the relative positions of the pins of a row in three successive positions of a rack coöperating with such row.

Fig. 16 is a fragmental view showing the pins illustrated in Figs. 13, 14 and 15 in end elevation.

Fig. 17 is a view showing the actuating mechanism for the manually-operated racks of the tabulating mechanism in plan view.

Fig. 18 is a fragmental side elevation showing a rack with its actuating mechanism of the manually-operated tabulating mechanism.

Fig. 19 shows in perspective the shaft on which the handle of the restoring means of the manually-operated tabulating mechanism is mounted.

Fig. 20 is an elevation of the link on the shaft illustrated in Fig. 19.

Fig. 21 is an elevation of the bracket connected to the shaft illustrated in Fig. 19.

Figs. 22 to 25 inclusive are enlarged detail views of the links and brackets of the means 6 for actuating the racks of the manually operated tabulating mechanism.

In the embodiment shown there is provided a main frame A having a card-analyzing mechanism to the left and a tabulating mechanism to the right, (Fig. 4).

The card-analyzing mechanism consists essentially of a card supply 21 having a vertically movable platform 22 mounted on a rod 23 which is provided with a spring 24 15 which exercises an upward tension on the platform 22 so as to keep the card supply 21 snug against the horizontally reciprocating card feed 25 in position for its uppermost card to be fed between the feed rolls 20 26 which in turn feed the card between the guide and die plates 27 and 28 respectively. The latter are correspondingly perforated, the perforations corresponding to the number of indications on the cards to be analyzed. Above the guide-plate 27 is formed 25 another plate 29 perforated similarly, in the perforations of which the upper ends of a plurality of extension pins 30 are normally disposed. The extension pins 30 are adapted 30 to extend upwardly through the plate 29 to be engaged by the racks 32 reciprocally mounted on the plate 29, the plate 29 forming the floor of the housing for the racks 32 which housing has a rear wall 33 having 35 openings therethrough to permit the rear extensions of the racks 32 to extend therethrough when in idle or non-analyzing position. The front wall 34 of the housing has an upper wall member 35 on the top of 40 which the frame 36 of the retractor reciprocates and is guided, the frame 36 being connected to the upper ends of the levers 37 which are pivotally connected at their lower ends to the frame A and suitably cam 45 driven. The front wall 34 is provided with a series of springs 38 which are connected to the front ends of the racks 32 and draw the same forward when they are released. On the rear end of the wall 35 an insulating 50 member 39 is secured on which a series of contacting springs 40 are connected, each of which is independently connected by suitable wires 41 with an electro-magnet 42, (Fig. 7) the wires 41 being each connected 55 to an individual contact 47 on the switch-board 48 by a wire 49. The upper edge of each rack 32 is provided with a series of lugs 43 adapted, when such rack is drawn forwardly, to engage the front downwardly extending end of a spring 40 disposed above it. Above the card supply 21 there is mounted 60 an insulation 44 on which a second series of contacting springs 45 are mounted, one for each rack 32, the front end of each of which 65 springs 45 is continually in engagement with

the rear upper edge of one of said racks. Each of these springs 45 is connected by a suitable wire 46, (Fig. 7) to a common lead 110 which in turn is connected to a main contact 109 on the switch-board by a wire 50. 76

Below the die plate 28 there is vertically reciprocally mounted a pin box 52, which is provided with a series of pins 53 having shoulders 54 which are normally held against the plate 55 of such pin-box 52 by springs 56, the plate 55 being perforated to permit the pins 53 to extend therethrough. When the pin box in the course of its operation is raised by its cams B, its pins are raised and those that find perforations in the card disposed between the plates 27 and 28 pass therethrough and engage the extension pins 30 in alinement with them and raise them into the paths of movement of the racks 32, while the other analyzing pins 53 are obstructed by the card. The anchoring members of the racks 32 are released by such upward movement of the engaged extension pins 30, and thereupon the racks 32 are permitted to be drawn forward by their respective springs 38 and while so moving forwardly will successively make and break a circuit by means of its lugs 43 raising and releasing the spring contacts 40.

The anchoring members (Fig. 10) consist of a plurality of latches 57 each fulcrumed on a bar 195 disposed on the rear side of the rear extension pins 30, the upper ends of the latches 57 terminating in stops 196 to engage the front ends of the racks 32 when they are disposed in initial position, while the lower ends of the latches 57 are pivotally connected to bars 197 extending parallel with and between the rows of extension pins 30. The front ends of the bars 197 are 105 pivotally connected to links 198 pivotally connected to a shaft 199 suspended from the plate 29. The rear ends of the bars 197 are connected by springs 200 to the bar 201 disposed below the bar 195 by means of which 110 springs 200, the bars 197 are normally maintained in depressed position in which position the stops 196 of the latches 57 are maintained in raised position in front of the racks 32, the plate 29 being provided with 115 a series of openings to permit the stops 196 to extend therethrough when in raised position.

Each of the extension pins 30 is provided with a stop 202 adapted to be engaged by 120 the bar 197 and to be thereby retracted when it has been advanced. From the foregoing, it will be seen that when an analyzing pin 53 finds a perforation in a card, it engages the extension pin 30 registering therewith which 125 in turn engages the bar 197, which bar 197 tilts a latch 57 to release a rack 32, whereupon such rack 32, by its springs 38, will be drawn forwardly until its front end strikes the protruding extension pin 30. On the 130

other hand, when the pin-box 52 is retracted with its analyzing pins 58, the advanced pin 53 will be withdrawn whereby the prop for the bar 197 is destroyed, and thereupon the 5 spring 200 of the raised bar 197 will be permitted to withdraw such bar 197 which in turn will thereby withdraw the advanced extension pin 30, and simultaneously therewith strain the stop 196 of the latch 57 10 against the lower edge of the released rack 32 if such rack has not yet been restored by the frame 36, and immediately when said rack 32 is restored to its initial position, the stop 196 of the latch 57 will project out and again engage the front edge of said rack 32 to anchor the same in initial position. 15

The frame 36 for restoring the racks 32, as aforesaid, is slidably mounted on the plate 35 and comprises essentially a universal 20 rack-engaging bar 203 adapted, when advanced to its rearmost position, to engage the upwardly extending portions 204 of all of the racks 32, and on the other hand to restore the advanced racks 32 when the frame 36 is so being actuated to its rearmost position. The front end of the frame 35 is provided with a transversely extending bar 205 of a length greater than the width of the plate 35 so that its ends extend over the upper ends of the levers 37, such outwardly extending ends being provided with openings through which the upper ends of the levers 37 extend thereby connecting such frame 36 with the levers 37. The levers 37 are suitably connected to the cam D so as to be actuated thereby that substantially simultaneous with the restoration of the pin-box 52, they will actuate the frame 36 in order that its universal bar 203 will restore any advanced 30 racks 32 in time to be anchored by the released latches 57, and after having so restored the racks 32, thereupon to withdraw the frame 36 to its initial forward position out of the paths of movement of the upward extensions 204 of the racks 32. 40

45

The tabulating and adding mechanism comprises a plurality of type-carrying sectors 58 such as disclosed in my co-pending application Serial No. 802362 filed Nov. 22, 50 1913. The sectors 58 in the present instance are distinguished from the prior art in that they are set electrically instead of mechanically. Below each sector 58 there is provided a series of pins 59 which are vertically reciprocally mounted in the plates 60 and 61, the lower ends of which pins 59 are adapted to extend into the paths of movement of the rollers 62 on the racks 63 by means of which they are raised, there being 60 a rack for each row of pins 59 so that only one pin in a row will at any time be actively set. The racks 63 are each provided with a longitudinally extending slot 206 through which extend two bars 207 common to all 65 the racks 63 and suitably mounted in the

frame of the tabulating mechanism, the racks 63 being supported by such bars 207, and the slots 206 being of such length relative to the distance between the remote sides of the bars 207 that the racks 63 can be reciprocated on said bars 207 by the escapement mechanism 68 about to be described. 70

The racks 63 are each provided with an upward extension 64 at its forward end. Just below the front of the lower plate 61 75 there is provided an anchoring bar 65 having a series of pins 65' to which a series of springs 66 are attached, each connected to one of the extensions 64 of the racks by means of which springs 66 the racks 63 are 80 moved rearwardly to engage the lower ends of the pins 59 for setting them. The racks 63 are each provided with a series of inclined teeth 67 adapted to coöperate with an escapement mechanism 68, one escapement 85 mechanism for each rack 63. The escapement mechanism comprises essentially a rock-plate 69 pivoted at 70 (Fig. 11) and having a downwardly extending finger 71 provided with a contact 72 adapted to co-operate and be attracted by an electro-magnet 42, thereby swinging the rock-plate 68 about its pivoted point 70, each plate 69 being connected by a spring 73 to a universal bar 74 by means of which the rock-plate is 95 returned to initial position when the electro-magnet is again deenergized. The rock-plate 69 is further provided with two pawls 75 and 76 (Figs. 4 and 11), one to engage the teeth 67 to the exclusion of the other, 100 and to permit the rack 63 to be advanced but one tooth at a time. Thus, whenever a circuit is made by a lug 43 of the rack 32 raising a spring contact 40, an electro-magnet 42 is energized and simultaneously therewith a 105 rack 63 advanced one tooth. Immediately that the rack 32 is drawn beyond the tooth first engaged, the circuit is broken, (Figs. 8 and 10) and thereby the electro-magnet de-energized and the rock-plate 69 permitted to 110 return to its initial position, and in turn, when the rack 32 is further advanced so that the next succeeding lug 43 engages the spring contact, the electro-magnet is again 115 energized and the rack 63 advanced the distance of another tooth. When retracting the racks 32, obviously the lugs 43 would again engage the spring-contacts 40 and thus, unless provision were made to prevent it, the electro-magnets 42 would again swing the 120 rock-plate 69. To prevent the rock-plates being swung on the return movement of the racks 32, a universal plate or bar 77 is provided at the upper ends of two levers 78 which are pivoted on the bar 79. Each of 125 the rock-plates 69 is provided with a rear extension adapted to be engaged by the plate 77 when the plates 69 are not to be attracted by the electro-magnets 42. One of the levers 78 is provided with a rear extension 81 130

adapted to be engaged by a stop 82 on the lever 83 fulcrumed at 84 with its lower end pivotally connected to a rod 85, the front end of which is provided with a sleeve 193

5 to be engaged by the rear end of the rod 87 the front end of which is pivotally connected to a lever 188 fulcrumed at its middle to the bracket 189, the upper end of which lever 188 is provided with a roller 190 in engagement with the cam C. The levers 78 are normally maintained in a rearward position by a spring 286 so that the rear extension 81 is continually in engagement with the stop 82. The arrangement is such that the cam 15 C, when the racks 32 and 63 are to be retracted, will actuate the rod 85 thereby swinging the lever 83 to tilt the levers 78 forward so that the universal plate 77 will slide under the projections 80 of the rock- 20 plates 69 and thereby anchor the same from being attracted by the electro-magnets 42 when the racks 32 are being retracted. Obviously, the rock-plates 69 will all have to be released and disposed in their initial position before such universal plate 77 can be 25 slid under their extensions 80 and this is assured in that the cam C is timed so that it will not move the rod 85 until all the racks 32 have come to a stop against one of the 30 pins 30 in which position, as shown in Figs. 8 and 10, the spring contacts 40 are spaced from the lugs 43 and thus do not form a circuit to energize the magnets 42, but on the other hand permit the rock-plates 69 to be 35 moved to initial position by the springs 73.

Simultaneously with the movement of the levers 78 by the lever 83 the racks 63 will be returned to initial position by means of the universal bar 87 connected between the upper ends of the lever 83, and the link 191, the lower end of which is fulcrumed to the shaft 84, which bar 87 is disposed in the paths of movement of the racks 63 and will engage the rear ends of the same when the 40 rod 85 is actuated by its cam C. When the racks 63 have been moved to initial position they will be held in such initial position by the pawls 76 of the escapement mechanism 68.

45 The cams D for actuating the levers 37 to retract the racks 32 are timed to come into operation after the cam C has actuated the rod 85 so that the rocking-plates 69 will have been anchored against movement by the magnets 42 before the racks 32 have begun their return movement.

50 The switch-board 48 is of novel construction. In the first place, it should be noted that preferably the pins 30 of the analyzing mechanism are divided into sets of at least five each so that only one class of data will be tabulated at any one time. For this purpose, in the present instance, we have provided twenty rows of pins and again divided 55 these rows into four sets of five rows of pins each. The switch-board 48 is therefore provided with four sets of contacts 47, five contacts 47 in each set, which are preferably disposed in a circular line, illustrated in Fig. 7 as a circular piece of insulation 88. The insulation 88 forms the outer ring of a series of concentric insulation rings 89, 90, 91, 92, 93 and 94, one smaller than the other progressively, and each two successive insulation rings spaced from one another by 70 75 80 85 90 95 100 105 110 115 120 125 130

conducting ring, of which conducting rings there are six, the conducting ring 95 between the insulation rings 88 and 89, the conducting ring 96 between the insulation rings 89 and 90, the conducting ring 97 between the insulation rings 90 and 91, the conducting ring 98 between the insulation rings 91 and 92, the conducting ring 99 between the insulation rings 92 and 93, and the conducting ring 100 between the insulation rings 93 and 94. Inside of the insulation ring 94, which latter insulation ring may be in the form of a disk, there is pivotally mounted a conducting arm 101 which is provided with a segment at its outer end. The arm 101 is of sufficient length to extend from the inner insulation ring 94 to and beyond the outer insulation ring 88 and is provided with five contacts 103 each one adapted to continually engage with one of the 95 conducting rings 96 to 100 inclusive, each of which contacts 103 is connected by a wire 104 to one of the contacts 105 of which there are five formed in a curved row in the segment 102. The arm 101 is adapted to be 100 105 110 115 120 125 130

swung around its pivotal point in which movement its contacts 103 are continually in engagement with the conducting rings 96 to 100 inclusive, and the contacts 104 are so spaced apart that when the segment 102 is 105 110 115 120 125 130

swung over a set of contacts 47, such contacts 104 may register with such set of contacts 47. The segment 102 is also provided with two other contacts 106 and 107 connected to one another by wire 108. The contact 106 is adapted to register with and continually engage the conducting ring 95 and the contact 107 is adapted to engage with any one of the contacts 109, of which there are four in the present instance, each of which is connected by a wire 50 to a second wire 110 which is connected to the wires 46 of the several spring contacts 45. The arrangement is such that whatever set of pins is to be connected to the tabulating mechanism, the arm 101 is swung around so that its contact 107 engage that contact 109 which is in connection with the set of pins to be connected to the tabulating mechanism. In such position, the circuits will be formed, (see Fig. 7) from the battery 111 through the common lead 112 to the conducting ring 95, then through the contact 106, the wire 108, the contact 107, the contact 109, the wires 50, 110 and 46 to the spring contacts 45, the lugs 43, the 130

spring contacts 40, the wires 41 to the magnets 42, the common lead 113 and back by the wire 114 to the battery 111. The foregoing circuits are made when the tabulating mechanism is operated from the main shaft 115 of the analyzing mechanism. The switch-board 48 as shown in Figs. 2-5 is provided with a handle 116 whereby the same can be rotated from one contact 109 to the other.

Should it be desired at any time to set the tabulator by hand instead of by the analyzing mechanism, or it be necessary in order to correct an item erroneously set, that certain or all of the items of the tabulator be set by hand, this can be done by the hand-operated mechanism disposed adjacent to the tabulating mechanism and directly in front of the same. This consists essentially of a frame 117 on which are mounted a series of racks 118 between guides 119 secured on said frame 117 and extending in an inclined direction, the lower ends of the guides 119 being connected to the plate member 120 under which the lower ends of the racks 118 are adapted to slide in the operation of the same and on which plate 120 the hands of the operator generally rest while operating the racks 118.

The upper surfaces of the racks 118 are provided with a series of successive notches 121 numbered consecutively and which notches are adapted to be engaged by the fingers of the operator. The lower surfaces of the racks 118 are provided with a series of teeth 122 corresponding in number to the number of notches 121, and in the present instance shown as disposed immediately below the notches 121. At the upper ends of the series of teeth 122 there is provided in each rack an additional notch 123 which is substantially V-shaped as distinguished from the teeth 122 which have one inclined surface and the other substantially perpendicular to the rack proper. Below each rack 118 there is provided a pawl 124, there being one pawl for each rack which are all pivotally mounted on a bar 125, each pawl 124 having a tooth 126 near its upper end for engaging the teeth 122 of the racks 118 and a downwardly extending lug 129 at its extreme upper end and at its other end is provided with a spring 127 connected to the frame 117 whereby the pawls are normally maintained in engagement with the teeth 122. Between the lower end of each pawl 124 and its pivotal connection there is provided on its lower side, a nose 128 for engagement with the universal plate 130 which is attached to the lower surfaces of brackets 131. The brackets 131 each have a slot 132 extending substantially their entire length through which slots the shaft 125 extends and on which shaft the brackets 131 ride.

Extending from the upper surfaces of the

brackets 131 at their front ends, there are formed bifurcations 133, in the slot of one of which is disposed the stop 134 of a lever 135 fixed to a shaft 136, the lever 135 being normally maintained in initial position by a spring 137 extending between the middle portion of its arm and the plate 120, and in the slot of the bifurcation 133 of the other bracket 131 is disposed the stop 132 of a lever 138, (Figs. 19 and 20) also fixed to the shaft 136.

Disposed below each rack 118 there are formed two contacts 138 and 139 properly insulated from one another and normally having their contacting portions spaced from one another. The contacts 138, as shown in Fig. 7, are connected by wires 140 to the wires 141 which in turn are connected by the wires 142 and 112 to the battery 111. The contacts 139 are each connected to one of the conducting rings 96 to 100 inclusive. From the conducting rings 96 to 100 inclusive the connection is continued through the contacts 103, wires 104, contacts 105, wires 49 and 41, magnets 42, common lead 113, 90 and then back to the battery 111 by the wire 114. Each contact 138 is disposed in contact with the lug 129 of a pawl 124. From the foregoing it will be seen that whenever a rack 118 is moved forwardly each of its teeth 122 will engage and successively depress the upper end of a pawl 124. The arrangement is such that when a pawl 124 is so depressed it will carry its adjacent contact 138 into contact with a contact 139 and thereby form a circuit to energize a magnet 42 similarly as do the contacts of the lugs 43 with the spring contacts 36.

For returning the racks 118 to their initial position by hand, the lever 135 is provided. Fixed to the shaft 136 on which the lever 135 is secured, there is provided a downwardly depending arm 144, preferably the continuation of the lever 193, which is pivotally connected by a link 145 to the front downwardly extending arm 146 of a rocker-plate 147 which is pivotally mounted on the shaft 148 to the frame 117. The plate 147 is provided with a downwardly extending arm 149 at its front end having a stop 115 thereon for engagement with the nose 151 near the lower end of the lever 152 and is secured to a bar 153 at its upper end which bar is connected to another lever similar to the lever 152 and also pivoted at its lower end. Each of the racks 118 is provided with a lug 154 at its upper end to be engaged by the bar 153 which extends across all of the racks and in its initial position rests on the racks 118 adjacent to the notches 121. Whenever the handle 135 is swung for retracting any of the racks 118 that had been set, the stop 134 will first, by its engagement with the bifurcation 133, move the brackets 131 and thereby the plate 130 rearward into 120 125 130

contact with the noses 128 of the pawls 124 whereby the pawls will be tilted out of engagement with the teeth 122 of the racks 118 and then upon the continued movement of the lever 135, the arm 144 through the link 145 will swing the rock plate 147 so that its stop 150 will strike the nose 151 of the lever 152 and thereby swing the lever 152 with its bar 153. The lugs 154 being disposed in the path of movement of the bar 153, the bar 153 will engage such lugs 154 and move the racks 118 to their initial position whereupon the release of the lever 135 will permit the pawls 124 to again engage the teeth 122 and lock the racks 118 in place.

Simultaneous with such retraction of the racks 118, by the operation of the handle 135, the racks 63 will be returned. This is accomplished by link 155 (Fig. 24) which has an elongated arm 156 an enlargement on one side of said arm provided with a slot 157 substantially parallel to said arm 156 (Fig. 24) and a further enlargement above said slot 157 on the other side of said arm 156 provided with an L-shaped slot 158. Said link is pivotally connected at its lower end to the upper horizontal arm of the bell crank 159 (Fig. 4) which is pivotally connected to the frame 117 at its angle, the lower end of the vertical arm of which bell crank 159 is bifurcated, the slot of which engages a stop on the sleeve 193 of the rod 85. The rock-plate 147 is provided with a rearwardly extending arm 161 (Figs. 23 and 25) having a stop 162 at the end thereof which normally lies in the corner 163 of the L-shaped slot 158. From the foregoing, it will be seen that whenever the rock-plate 147 is rocked by the operation of the lever 135, its stop 162 engaging the lower surface of the slot 158 depresses the link 155 which in turn actuates the bell crank 159 to advance the rod 85 thereby to actuate the lever 83 to retract the racks 63.

To retract the racks 118 through the main shaft 115, there is provided a bent lever 164 (Fig. 22) pivotally connected at its angle to the shaft 165 mounted in the frame 117, the lower end of the downwardly extending arm 166 (Fig. 22) of the bent lever 164 having a stop 167 disposed in the slot 157 of the lever 155. Mounted on the shaft 165 and parallel with the upwardly extending arm 168 of the lever 164 there is provided a short lever 169 (Fig. 22) to the free end of which short lever 169 and upwardly extending arm 168 there is secured a universal bar 170 having a V-shaped upwardly extending edge to engage the V-shaped notches 123 of the racks 118 when the racks 118 are all in their initial position.

From the foregoing, it will be seen that whenever a rack is moved downward out of initial position, the bar 170 will be depressed out of the notches 123 and be dis-

posed against the edge 171 of such downwardly moving rack 118, and simultaneously with such depressing of the bar 170, the stop 167 of the bent lever 164 will swing the link 155 to one side so that the stop 162 (Figs. 23 and 25) of the rock-plate 147 will ride into the toe 172 (Fig. 24) of the slot 158. Thereupon, when the link 155 is moved downwardly by the actuation of the bell crank 159, the stop 162 engaging the upper surface 173 of the toe 172, will swing the rock-plate 147 so that its stop 150 will engage the nose 151 of the lever 152 which lever 152 through its bar 153 will retract the racks 118 to initial position.

The actuation of the bell crank 159 and rod 85 by the shaft 115 is accomplished by means of the cam C actuating the roller 190 of the lever 188 which in turn actuates the rod 87, which by its engagement with the sleeve 193 actuates the bell crank 159 and the rod 85. Thus the rod 85 may be actuated by the bell crank 159 without disturbing the rod 187 and in turn the rod 187 may actuate both the bell crank 159 and the rod 85.

Preferably the bent lever 164 is provided with a spring 178 for normally maintaining the bar 170 snugly in the notches 123 or against the lower surface 171 of a rack or racks 118.

So that the contacts 138 and 139 may be swung out of engagement with the pawls 124 when the racks 118 are retracted, and thus be prevented from energizing the magnets 42 on the return movement of the racks 118, the insulation on which the contacts 138 and 139 are mounted are all connected to a plate 180 fixed to the rock-plate 147 and an auxiliary rock-plate 194. Thus since the rock-plates 147 and 194 are always rocked whenever the racks 118 are returned, the contacts 138 and 139 are also rocked and so rocked that they come out of engagement with the pawls 124.

The pins 59 are each provided, (Figs. 13 to 16) with an upper notch 181 to engage the plate 60 and a lower notch 182 to engage the plate 61 whereby the pins are anchored to said plates 60 and 61. A novel arrangement is provided whereby only one pin will be extended at a time. This is accomplished by means of crescent-shaped cams. Each pin 59, except the last, has pivotally connected to it an upper crescent-shaped cam 183 having its surface adapted to engage with the lower surface of the plate 60 and the other end of its straight surface in engagement with a lug 184 on the next adjacent pin 59, each pin except the first being provided on the other side of it adjacent to the cam 183 with such pin 184. Each pin, except the first, is also provided with a lower crescent-shaped cam 185, which is pivotally connected at one end

to the pin 59 below the plate 61 so that its upper curved surface is adapted to engage the lower surface of the plate 61 and the other end of its straight surface is adapted to engage a lug 186 on a preceding pin 59, each pin except the last being provided with such lug 186 adjacent to the cam 185.

From the foregoing, it will be seen that as the roller 62 engages the first pin 59, it will merely raise the first pin without disturbing the second pin, but upon engaging the second pin (see Fig. 14) and the lug 184 will engage the cam 183 it will by its engagement with the lower surface of the plate 60 depress the first pin 59. In its return movement, the roller 62 by engagement with a second or succeeding pin 59, the lug 186 of an engaged pin will raise the cam 185 of a preceding pin and thus by means of its engagement with the lower surface of the plate 61 will depress or return the preceding pin 59 to its initial position. By this arrangement no springs are required.

It is obvious that various changes and modifications may be made to the details of construction without departing from the general scope of the invention.

I claim:

1. In an accounting machine the combination with a card analyzing mechanism having a plurality of settable racks and a plurality of pins for defining the positions of said racks, of a tabulating mechanism having a plurality of settable racks, and electrical means for actuating the racks of said tabulating mechanism by the operation of the racks of said analyzing mechanism.

2. In an accounting machine, the combination with a card analyzing mechanism comprising a plurality of pins adapted to be positioned according to the record of a card being analyzed, slideable means adapted to be actuated into a corresponding position, of a tabulating mechanism having a plurality of pins, means for setting said pins, and electrical means for actuating said setting means by the actuation of said slideable means.

3. In an accounting machine, the combination with a card analyzing mechanism having record reproducing means, of a tabulating mechanism having a plurality of type-carrying sectors, pins for defining the positions of said sectors, and electrical means for actuating said pins to correspond with the position of said record reproducing means.

4. In an accounting machine, the combination with an analyzing mechanism having a plurality of rows of pins, a rack for each row, said racks being movable and adapted to register with a pin having been actuated, a plurality of electrical conducting lugs on each rack corresponding to the number of

pins in a row, a contact disposed in the path of movement of the lugs of each rack and adapted to be engaged by said lugs a number of times corresponding to the denomination of the pin actuated, of a tabulating mechanism having a plurality of type-carrying sectors one for each row of pins, a plurality of pins adapted to position said sectors, a plurality of racks for actuating said pins, tension means for actuating said racks, escapement mechanisms for anchoring said racks against movement by said tension means, and electrical means for actuating said escapement mechanisms by the contact of said lugs with said contacts.

5. In an accounting machine, the combination with an analyzing mechanism having a plurality of rows of pins, a rack for each row, said racks being movable and adapted to register with a pin having been actuated, a plurality of electrical conducting lugs on each rack corresponding to the number of pins in a row, a contact disposed in the path of movement of the lugs of each rack and adapted to be engaged by said lugs a number of times corresponding to the denomination of the pin actuated, of a tabulating mechanism having a plurality of type-carrying sectors one for each row of pins, a plurality of pins adapted to position said sectors, a plurality of racks for actuating said pins, tension means for actuating said racks, escapement mechanisms for anchoring said racks against movement by said tension means, and electrical means for actuating said escapement mechanisms every time lugs of corresponding analyzing racks contact with their contacts whereby the corresponding tabulating racks are actuated to positions corresponding with the positions of the corresponding analyzing racks.

6. In an accounting machine, the combination with an analyzing mechanism having a plurality of racks adapted to be positioned according to the record of a card, a plurality of electrical conducting lugs on each rack corresponding to the denominations of a data row of said card, a contact disposed in the path of movement of the lugs of each rack and adapted to be engaged a number of times corresponding to the record to be reproduced, of a tabulating mechanism having a plurality of type-carrying sectors one for each rack of said analyzing mechanism, a plurality of racks for positioning said sectors, tension means for actuating said racks, escapement mechanisms for anchoring said racks against movement by said tension means, and electrical means for actuating said escapement mechanisms by the contact of said lugs with said contacts.

7. In an accounting machine, the combination with an analyzing mechanism having a plurality of racks adapted to be positioned according to the record of a card, a plurality

of electrical conducting lugs on each rack corresponding to the denominations of a data row of said card, a contact disposed in the path of movement of the lugs of each 5 rack and adapted to be engaged a number of times corresponding to the record to be reproduced, of a tabulating mechanism having a plurality of type-carrying sectors one for each rack of said analyzing mechanism, 10 a plurality of racks for positioning said sectors, tension means for actuating said racks, escapement mechanisms for anchoring said racks against movement by said tension means; and electrical means for actuating 15 said escapement mechanisms every time lugs of corresponding analyzing racks contact with their contacts whereby the corresponding tabulating racks are actuated to positions corresponding with the positions of 20 the corresponding analyzing racks.

8. In an accounting machine, the combination with an analyzing mechanism having a plurality of racks adapted to be positioned according to the record of a card, a plurality 25 of electrical conducting lugs on each rack corresponding to the denominations of a data row of said card, a contact disposed in the path of movement of the lugs of each rack and adapted to be engaged a number of 30 times corresponding to the record to be reproduced, of a tabulating mechanism having a plurality of type-carrying sectors one for each rack of said analyzing mechanism, sector-positioning means, a plurality of racks 35 for positioning said sector-positioning means, tension means for actuating said racks to position said sector-positioning means, escapement mechanisms for anchoring said racks against movement by said tension 40 means, and electrical means for actuating said escapement mechanisms every time lugs of corresponding analyzing racks contact with their contacts whereby the corresponding tabulating racks are actuated to positions 45 corresponding with the positions of the corresponding analyzing racks.

9. In an accounting machine, the combination with an analyzing mechanism having a plurality of racks adapted to be positioned according to the record of a card to be reproduced, a plurality of electrical conducting lugs on each rack corresponding to the denominations of a data row of said card, a contact disposed in the path of 50 movement of each row of lugs and adapted to be engaged a number of times corresponding to the record to be reproduced, of a tabulating mechanism having a plurality of type-carrying sectors one for each rack of 55 said analyzing mechanism, sector-positioning means, a plurality of racks for positioning said sector-positioning means, tension means for actuating said racks to position said sector-positioning means, escapement mechanisms for anchoring said racks 60 65

against movement by said tension means, electro-magnets one for each escapement mechanism and each connected to one of the contacts of said analyzing mechanism, a contact on each escapement mechanism 70 adapted to be attracted by its magnet every time it is energized by the contact of a thereto-connected contact with the lugs of its analyzing rack whereby the corresponding tabulating rack is actuated to a position 75 corresponding with the position of a corresponding analyzing rack.

10. In an accounting machine, the combination with an analyzing mechanism having a plurality of contacts, means for engaging said contacts a number of times corresponding to the denominations of a data row of the card to be recorded, of a tabulating mechanism having a plurality of type carrying sectors one for each contact of 80 said analyzing mechanism, sector-positioning means, a plurality of racks for positioning said sector-positioning means, tension means for actuating said racks to position said sector-positioning means, escapement 85 mechanisms for anchoring said racks against movement by said tension means, electro-magnets one for each escapement mechanism and each connected to one of the contacts of said analyzing mechanism, a contact on each 90 escapement mechanism adapted to be attracted by its magnet every time it is energized by contact of a thereto-connected contact of said analyzing mechanism whereby the corresponding tabulating rack is actuated to a position 95 corresponding to the number of times the analyzing contact is engaged.

11. In an accounting machine, the combination with an analyzing mechanism having a plurality of contacts, means for engaging said contacts a number of times corresponding to the denominations of the card to be reproduced, of a tabulating mechanism having a plurality of type-carrying sectors 100 for each contact of said analyzing mechanism, pins for defining the position of said sectors, and electrical means for setting said pins in positions corresponding to the number of times the thereto-connected analyzing 110 contacts are engaged.

12. In an accounting machine, the combination with an analyzing mechanism having a plurality of contacts, means for engaging said contacts a number of times corresponding to the denominations of the card to be reproduced, said engaging means being disconnected from said contacts between successive engagements, and both before the first and after the final engagement 120 thereof, of a tabulating mechanism having a plurality of type-carrying sectors for each contact of said analyzing mechanism, pins for defining the positions of said sectors, and electrical means for setting said pins 125 130

in positions corresponding to the number of times the thereto-connected analyzing contacts are engaged.

13. In an accounting machine, the combination with an analyzing mechanism having a plurality of contacts, means for engaging said contacts a number of times corresponding to the denominations of the card to be reproduced, said engaging means being disconnected from said contacts between successive engagements, and both before the first and after the final engagement thereof, of a tabulating mechanism having a plurality of type-carrying sectors for each contact of said analyzing mechanism, pins for defining the positions of said sectors, electrical means for setting said pins in positions corresponding to the number of times the thereto-connected analyzing contacts are engaged, and means for restoring said type-carrying sectors and pins to initial position.

14. In an accounting machine, the combination with an analyzing mechanism having a plurality of contacts, means for engaging said contacts a number of times corresponding to the denominations of the card to be reproduced, said engaging means being disconnected from said contacts between successive engagements, and both before the first and after the final engagement thereof, of a tabulating mechanism having a plurality of type-carrying sectors for each contact of said analyzing mechanism, pins for defining the positions of said sectors, electrical means for setting said pins in positions corresponding to the number of times the thereto-connected analyzing contacts are engaged, means for restoring said type-carrying sectors to initial position, means for restoring the engaging means of said analyzing mechanism, and means for disconnecting said electrical means so that during the restoration of the engaging means of said analyzing mechanism the type-carrying sectors will not be advanced.

15. In an accounting machine, the combination with the frame of an analyzing mechanism, of a plurality of record producing racks slidably mounted on said frame, a plurality of type-carrying sectors of a tabulating mechanism one corresponding to each rack, pins for defining the positions of said sectors, electrical actuating means for setting said pins by the actuation of said racks, and means for restoring said racks and pins to initial position.

16. In an accounting machine, the combination with the frame of an analyzing mechanism, of a plurality of record producing racks slidably mounted on said frame, a plurality of type-carrying sectors of a tabulating mechanism one corresponding to each rack, electrical actuating means for connecting each sector with a rack and thereby actuating a sector, means for restoring said

racks to initial position, said restoring means comprising upward extensions on said racks, a universal bar disposed in the path of movement of said extensions, and means for actuating said bar into engagement with said extensions to thereupon return said racks to initial position.

17. In an accounting machine, the combination with the frame of an analyzing mechanism, of a plurality of record producing racks slidably mounted on said frame, a plurality of type-carrying sectors of a tabulating mechanism one corresponding to each rack, pins for defining the positions of said sectors, electrical actuating means for setting said pins by the actuation of said racks, means for restoring said racks and pins to initial position, and means for anchoring said racks in initial position.

18. In an accounting machine, the combination with the frame of an analyzing mechanism, of a plurality of record producing racks slidably mounted on said frame, a plurality of type-carrying sectors of a tabulating mechanism one corresponding to each rack, electrical actuating means for connecting each sector with a rack and thereby actuating a sector, means for restoring said racks to initial position, means for anchoring said racks in initial position, said anchoring means comprising latches one for each rack, and means for withdrawing a latch whenever a rack is to be actuated.

19. In an accounting machine, the combination with a perforated plate of an analyzing mechanism, of a plurality of rows of pins adapted to be distended through said plate, a plurality of racks slidably mounted on said frame one rack for each row of pins, tension means for advancing said racks into contact with said distended pins, retraction bars one for each row of pins, stops on said pins to be engaged by one of said retraction bars, and latches for locking said racks in initial position and pivotally connected to said retraction bars, said pins, when distended, actuating the bars engaged by them and thereby tilting said latches to release said racks.

20. In an accounting machine, the combination with a perforated plate of an analyzing mechanism, of a plurality of rows of pins adapted to be distended through said plate, a plurality of racks slidably mounted on said frame one rack for each row of pins, tension means for advancing said racks into contact with said distended pins, retraction bars one for each row of pins, stops on said pins to be engaged by one of said retraction bars, latches for locking said racks in initial position and pivotally connected to said retraction bars, said pins, when distended, actuating the bars engaged by them and thereby tilting said latches to release said racks, and means for retracting said re-

traction bars and thereby again actuating said latches into rack-anchoring position.

21. In an accounting machine, the combination with a perforated plate of an analyzing mechanism, of a plurality of rows of pins adapted to be distended through said plate, a plurality of racks slidably mounted on said frame one rack for each row of pins, tension means for advancing said racks into contact with said distended pins, retraction bars one for each row of pins, stops on said pins to be engaged by one of said retraction bars, latches for locking said racks in initial position and pivotally connected to said retraction bars, said pins, when distended, actuating the bars engaged by them and thereby tilting said latches to release said racks, and springs for retracting said retraction bars when said pins are released and thereby again actuating said latches into rack-anchoring position.

22. In an accounting machine, the combination with the frame of an analyzing mechanism, of a plurality of record producing racks slidably mounted on said frame, a plurality of type-carrying sectors of a tabulating mechanism one corresponding to each rack, electrical actuating means for connecting each sector with a rack and thereby actuating a sector, means for restoring said racks to initial position, said restoring means comprising upward extensions on said racks, a frame having a universal bar at its rear end disposed in the path of movement of said extensions, and a connecting bar at its front end, levers, the upper ends of said levers being connected to the ends of said front bar, and means for actuating said levers whereby said rear bar is moved into engagement with said extensions and thereupon returns said racks to initial position.

23. In an accounting machine, the combination with the frame of an analyzing mechanism, of a plurality of record producing racks slidably mounted on said frame, a rear smooth edge on each of said racks, a plurality of lugs on each rack corresponding to the number of data denominations in the row of a card to be recorded, electrical connecting means, a plurality of contacts one end of each of which is disposed in the path of movement of the lugs of one rack, the other end of each of which is connected to one of said connecting means, a plurality of type-carrying sectors of a tabulating mechanism one corresponding to each rack, electrical actuating means for actuating said sectors, a second set of electrical connecting means, a second plurality of contacts each of which is in constant engagement with the rear smooth edge of one of said racks and connected to one of said second electrical connecting means, said electrical actuating means being each connected to a pair of said electrical connecting means and adapted to be energized whenever said first contacts are engaged by lugs, said electrical connecting means being each connected to a pair of said electrical connecting means and adapted to

be energized whenever said first contacts are engaged by lugs.

24. In an accounting machine, the combination with the frame of an analyzing mechanism, of a plurality of record producing racks slidably mounted on said frame, a rear smooth edge on each of said racks, a plurality of lugs on each rack corresponding to the number of data denominations in the row of a card to be recorded, electrical connecting means, a plurality of contacts one end of each of which is disposed in the path of movement of the lugs of one rack, the other end of each of which is connected to one of said connecting means, a plurality of type-carrying sectors of a tabulating mechanism one corresponding to each rack, electrical actuating means for actuating said sectors, a second set of electrical connecting means, a second plurality of contacts each of which is in constant engagement with the rear smooth edge of one of said racks and connected to one of said second electrical connecting means, said electrical actuating means being each connected to a pair of said electrical connecting means and adapted to be energized whenever said first contacts are engaged by lugs, said lugs being spaced apart so that said contacts will be spaced therefrom when disposed between a pair of successive lugs.

25. In an accounting machine, the combination with the frame of an analyzing mechanism, of a plurality of record producing racks slidably mounted on said frame, a rear smooth edge on each of said racks, a plurality of lugs on each rack corresponding to the number of data denominations in the row of a card to be recorded, electrical connecting means, a plurality of contacts one end of each of which is disposed in the path of movement of the lugs of one rack, the other end of each of which is connected to one of said connecting means, a plurality of type-carrying sectors of a tabulating mechanism one corresponding to each rack, electrical actuating means for actuating said sectors, a second set of electrical connecting means, a second plurality of contacts each of which is in constant engagement with the rear smooth edge of one of said racks and connected to one of said second electrical connecting means, said electrical actuating means being each connected to a pair of said electrical connecting means and adapted to be energized whenever said first contacts are engaged by lugs, said first contacts being disposed to be disconnected from said lugs both before initial movement of said racks between engagement of successive lugs and after engagement with the last lug of a row.

26. In an accounting machine, the combination with a perforated plate of an analyzing mechanism, of a plurality of rows of

pins adapted to be distended through said plate, a plurality of racks slidably mounted on said frame one rack for each row of pins, means for advancing said racks into contact with said distended pins, retraction bars one for each row of pins, stops on said pins to be engaged by one of said retraction bars, links pivotally mounting said bars, and springs for retracting said retraction bars when said pins are released.

27. In an accounting machine, the combination with a tabulating mechanism having a plurality of type sectors, and a plurality of pins for defining the positions of said type sectors, of an analyzing mechanism for reproducing the records of cards, and electrical means for actuating said pins by the operation of said analyzing mechanism.

28. In an accounting machine, the combination of an analyzing mechanism adapted to actuate varying amounts corresponding respectively to the records to be reproduced; a tabulating mechanism having a plurality of racks; tension means for advancing said racks; rockable escapement means one for each rack adapted to prevent the advance of the racks and to permit the advance of the racks an increment each time the escapement means is rocked; electrical means operatively connected to the analyzing mechanism for automatically rocking the escapement means, when the analyzing mechanism is actuated, a number of times corresponding to the record to be reproduced which determines the amount of actuation of the analyzing means.

29. In an accounting machine, the combination of an analyzing mechanism adapted to actuate varying amounts corresponding respectively to the records to be reproduced; a tabulating mechanism having a plurality of racks; tension means for advancing said racks; rockable escapement means one for each rack adapted to prevent the advance of the racks and to permit the advance of the racks an increment each time the escapement means is rocked; electromagnets for rocking the escapement means; electrical means operatively connected to the analyzing mechanism and to the electromagnets for automatically rocking the escapement means, when the analyzing mechanism is actuated, a number of times corresponding to the record to be reproduced which determines the amount of actuation of the analyzing means.

30. In an accounting machine, the combination with a tabulating mechanism having a plurality of racks, of an analyzing mechanism for reproducing the records of cards, escapement mechanisms one for each of said racks for anchoring said racks against movement, tension means for advancing said racks when released by said escapement mechanisms, electro-magnets one for each es-

capement mechanism, an electrical contact on each escapement, and means for energizing said magnets by the operation of said analyzing mechanism, the energizing of said magnets attracting said contacts to rock said escapement mechanism a number of times corresponding to the record to be reproduced, the racks being successively advanced according to the number of times the escapement mechanisms are rocked.

31. In an accounting machine, the combination with a tabulating mechanism having a plurality of racks, of an analyzing mechanism for reproducing the records of cards, escapement mechanisms tiltably mounted one for each of said racks for anchoring said racks against movement, tension means for advancing said racks when released by said escapement mechanisms, electro-magnets one for each escapement mechanism, an electrical contact on each escapement, and means for energizing said magnets by the operation of said analyzing mechanism, the energizing of said magnets attracting said contacts to tilt said escapement mechanisms a number of times corresponding to the record to be reproduced, the racks being successively advanced according to the number of times the escapement mechanism is rocked whereby to release said racks.

32. In an accounting machine, the combination with a tabulating mechanism having a plurality of racks, a plurality of rows of pins to be engaged by said racks to reproduce records, of an analyzing mechanism for reproducing records comprising a plurality of analyzing racks, pins for defining the positions of said analyzing racks, and electrical means for actuating and defining the positions of the tabulating racks by the operation of said analyzing racks thereby to actuate the pins of said tabulating mechanism to reproduce corresponding records.

33. In an accounting machine, the combination with a tabulating mechanism having a plurality of racks, a plurality of rows of pins one row for each rack to be engaged by said racks to reproduce records, of an analyzing mechanism for reproducing records, escapement mechanisms one for each of said racks for anchoring said racks against movement, tension means for advancing said racks when released by said escapement mechanisms, and electrical means for rocking said escapement mechanisms by the operation of said analyzing mechanism a number of times corresponding to the record to be reproduced, the racks to be successively advanced according to the number of times the escapement mechanism is rocked, thereby to release said racks to permit them to be advanced to actuate said pins to reproduce corresponding records.

34. In an accounting machine, the com-

bination with a tabulating mechanism having a plurality of racks, a plurality of rows of pins one row for each rack, upward extensions one on each rack to engage one pin 5 of a row at a time, of an analyzing mechanism for reproducing records comprising a plurality of analyzing racks, pins for defining the positions of said analyzing racks, electrical means for actuating said tabulating racks by the operation of said analyzing racks thereby to actuate said pins to reproduce corresponding records.

35. In an accounting machine, the combination with a tabulating mechanism having a plurality of racks, of an analyzing mechanism for reproducing the records of cards, escapement mechanisms tiltably mounted one for each of said racks for anchoring said racks against movement, tension means 15 for advancing said racks when released by said escapement mechanisms, electro-magnets one for each escapement mechanism, an electrical contact on each escapement, means for energizing said magnets by the operation 20 of said analyzing mechanism, the energizing of said magnets attracting said contacts to tilt said escapement mechanisms thereby to release said racks, and means for anchoring said escapement mechanisms 25 against tilting when said analyzing mechanism is being restored thereby to prevent the repeated operation of said escapement mechanisms.

36. In an accounting machine, the combination with a tabulating mechanism having a plurality of racks, of an analyzing mechanism for reproducing the records of cards, escapement mechanisms tiltably mounted one for each of said racks for anchoring 35 said racks against movement, tension means for advancing said racks when released by said escapement mechanisms, electro-magnets one for each escapement mechanism, an electrical contact on each escapement, means 40 for energizing said magnets by the operation of said analyzing mechanism, the energizing of said magnets attracting said contacts to tilt said escapement mechanisms thereby to release said racks, extensions one 45 on each of said escapement mechanisms, rock plates, a universal bar supported by said rock plates, and means for swinging said rock plates so that said universal bar will engage the extensions of said escapement 50 mechanisms and anchor the same against tilting when said analyzing mechanism is being restored thereby to prevent the repeated 55 operation of said escapement mechanisms.

37. In an accounting machine, the combination with a tabulating mechanism having a plurality of racks, of an analyzing mechanism also having a plurality of racks 60 slidably mounted into position for reproducing records, a plurality of lugs on each

of said latter racks, a plurality of electrical contacts one for each of said latter racks and lying in the paths of movement of said lugs to be engaged thereby when said racks are moved for reproducing a record, escapement mechanisms tiltably mounted one for 70 each of the tabulating racks for anchoring them against movement, tension means for advancing said tabulating racks when released by said escapement mechanisms, electro-magnets one for each escapement mechanism and connected to one of the analyzing contacts, an electrical contact on each escapement mechanism, electrical connections whereby said magnets are energized a number of times corresponding to the number 80 of lugs that have engaged a thereto-connected analyzing contact, the energizing of said magnets attracting said contacts to rock said escapement mechanisms thereby to release said racks to permit them to be advanced to actuate said pins to reproduce corresponding records.

38. In an accounting machine, the combination with a tabulating mechanism having a plurality of racks, of an analyzing mechanism also having a plurality of racks 90 slidably mounted into position for reproducing records, a plurality of lugs on each of said latter racks, a plurality of electrical contacts one for each of said latter racks 95 and lying in the paths of movement of said lugs to be engaged thereby when said racks are moved for reproducing a record, escapement mechanisms tiltably mounted one for each of the tabulating racks for anchoring 100 them against movement, tension means for advancing said tabulating racks when released by said escapement mechanisms, electro-magnets one for each escapement mechanism and connected to one of the analyzing 105 contacts, an electrical contact on each escapement mechanism, electrical connections whereby said magnets are energized a number of times corresponding to the number 110 of lugs that have engaged a thereto-connected analyzing contact, the energizing of said magnets attracting said contacts to rock said escapement mechanisms thereby to release said racks to permit them to be advanced to actuate said pins to reproduce 115 corresponding records, means for restoring said analyzing mechanism, and means for anchoring said escapement mechanisms against tilting when said analyzing mechanism is being restored thereby to prevent the repeated 120 operation of said escapement mechanisms.

39. In an accounting machine, the combination with a tabulating mechanism having a plurality of racks, of an analyzing 125 mechanism also having a plurality of racks slidably mounted into position for reproducing records, a plurality of lugs on each

- of said latter racks, a plurality of electrical contacts one for each of said latter racks and lying in the paths of movement of said lugs to be engaged thereby when said racks 5 are moved for reproducing a record, escapement mechanisms tiltably mounted one for each of the tabulating racks for anchoring them against movement, tension means for advancing said tabulating racks when released by said escapement mechanisms, electro-magnets one for each escapement mechanism and connected to one of the analyzing contacts, an electrical contact on each escapement mechanism, electrical connections 10 whereby said magnets are energized a number of times corresponding to the number of lugs that have engaged a thereto-connected analyzing contact, the energizing of said magnets attracting said contacts to rock 15 said escapement mechanisms thereby to release said racks to permit them to be advanced to actuate said pins to reproduce corresponding records, means for restoring said analyzing racks, extensions one on each 20 of said escapement mechanisms, rock plates, a universal bar supported by said rock plates, and means for swinging said rock plates so that said universal bar will engage the extensions of said escapement mechanisms 25 and anchor the same against tilting when said analyzing racks are being restored thereby to prevent the repeated operation of said escapement mechanisms.
40. In an accounting machine, the combination with a tabulating mechanism having a plurality of racks, a plurality of rows of pins one row for each rack to be engaged by said racks to reproduce records, of an analyzing mechanism for reproducing records, escapement mechanisms one for each of said racks for anchoring said racks against movement, tension means for advancing said racks when released by said escapement mechanisms, electrical means for rocking 35 said escapement mechanisms by the operation of said analyzing mechanism a number of times corresponding to the record to be reproduced, the racks to be successively advanced according to the number of times the 40 escapement mechanism is rocked, thereby to release said racks to permit them to be advanced to actuate said pins to reproduce corresponding records, and means for restoring said racks.
41. In an accounting machine, the combination with a tabulating mechanism having a plurality of racks, of an analyzing mechanism for reproducing the records of cards, comprising a plurality of analyzing racks 45 and pins for defining the positions of said analyzing racks, electrical means for actuating said tabulating racks by the operation of said analyzing racks, a retracting bar disposed to travel in the path of movement of the rear ends of the tabulating racks, and means for actuating said retracting bar into engagement with said latter racks and restore them to initial position.
42. In an accounting machine, the combination with a tabulating mechanism having a plurality of racks, a plurality of rows of pins one row for each rack to be engaged by said racks to reproduce records, of an analyzing mechanism for reproducing records, escapement mechanisms one for each of said racks for anchoring said racks against movement, tension means for advancing said racks when released by said escapement mechanisms, electrical means for actuating said escapement mechanisms by the operation of said analyzing mechanism thereby to release said racks to permit them to be advanced to actuate said pins to reproduce corresponding records, a retracting bar disposed to travel in the path of movement of the rear ends of the tabulating racks, and means for actuating said retracting bar into engagement with said latter racks and restore them to initial position, the escapement mechanisms permitting the restoration of said racks, but locking the racks against advance movement.
43. In an accounting machine, the combination with a tabulating mechanism having a plurality of racks, of an analyzing mechanism for reproducing the records of cards, escapement mechanisms one for each of said racks for anchoring said racks against movement, tension means for advancing said racks when released by said escapement mechanisms, electrical means for actuating said escapement mechanisms by the operation of said analyzing mechanism, a retracting bar disposed to travel in the path of movement of the rear ends of the tabulating racks, and means for actuating said retracting bar into engagement with said latter racks and restore them to initial position, the escapement mechanisms permitting the restoration of said racks, but locking the racks against advance movement.
44. In an accounting machine, the combination with a tabulating mechanism having a plurality of racks, of an analyzing mechanism for reproducing the records of cards, escapement mechanisms one for each of said racks for anchoring said racks against movement, tension means for advancing said racks when released by said escapement mechanisms, electrical means for actuating said escapement mechanisms by the operation of said analyzing mechanism, and means for anchoring said escapement mechanisms against tilting when said analyzing mechanism is being restored thereby to prevent the repeated operation of said escapement mechanisms.
45. In an accounting machine, the combination with an analyzing mechanism hav-

ing a plurality of sets of record reproducing members, a plurality of electrical contacts for said record reproducing members divided into sets corresponding with said 5 sets of record reproducing members, of a tabulating mechanism having a plurality of type-carrying sectors divided into sets corresponding to the sets of said record reproducing members, actuating means for operating 10 said type-carrying sectors also divided into sets, electrical connections connecting each actuating means with a corresponding electrical contact, a switch having a plurality of stationary contacts one for each set 15 of record reproducing means, electrical connections each connecting one of said stationary contacts with a set of record reproducing electrical contacts, a source of current, an annular conducting member on said 20 switch, an electrical connection connecting said conducting member with said source of current, an electrical connection connecting all of said actuating means with said source of current, and a rotatably mounted switch 25 arm on said switch for independently connecting each of said stationary contacts with said conducting member so that only one set of actuating means may be operated at any one time.

30 46. In an accounting machine, the combination with an analyzing mechanism having a plurality of sets of record reproducing members, a plurality of electrical contacts for said record reproducing members divided into sets corresponding with said sets 35 of record reproducing members, of a tabulating mechanism having a plurality of type-carrying sectors divided into sets corresponding to the sets of said record reproducing members, actuating means for operating 40 said type-carrying sectors also divided into sets, electrical connections connecting each actuating means with a corresponding electrical contact, a switch having a plurality 45 of stationary contacts one for each set of record reproducing means, electrical connections each connecting one of said stationary contacts with a set of record reproducing electrical contacts, a source of current, 50 an annular conducting member on said switch, an electrical connection connecting said conducting member with said source of current, an electrical connection connecting all of said actuating means with said source 55 of current, and a rotatably mounted switch arm on said switch for independently connecting each of said stationary contacts with said conducting member so that each set of electrical contacts may be connected to and 60 operate a corresponding set of actuating means to the exclusion of the other sets.

47. In an accounting machine, the combination with an analyzing mechanism divided into a plurality of sets, of a tabulating mechanism divided into a plurality of sets corre-

sponding to the sets of said analyzing mechanism and adapted to be operated by said analyzing mechanism, electrical connections connecting each set of the analyzing mechanism with a set of tabulating mechanism, a 70 switch having a plurality of stationary contacts one for each set of the analyzing mechanism, electrical connections each connecting one of said stationary contacts with a set of analyzing mechanism, a source of current, a 75 common conducting member on said switch, an electrical connection connecting said conducting member with said source of current, an electrical connection connecting all of said sets of the tabulating mechanism with 80 said source of current, and a removable switch arm on said switch for independently connecting each of said stationary contacts with said conducting member so that each set of the analyzing mechanism may be connected to operate a corresponding tabulating mechanism to the exclusion of the other sets.

48. In an accounting machine, the combination with a main driving shaft, of a 90 tabulating mechanism driven by said main driving shaft and having a plurality of racks for setting said tabulating mechanism, an analyzing mechanism also driven from said main driving shaft and adapted to operate said racks, a retracting bar for engaging and resetting said racks to initial position, means operated by said main driving shaft for actuating said retracting bar, means for operating said retracting bar independently of said driving shaft when said driving shaft is at rest, and a mechanism for resetting said tabulating mechanism independently of said analyzing mechanism when said racks have been so reset. 105

49. In an accounting machine, the combination with the main driving shaft, of a tabulating mechanism driven by said main driving shaft and having a plurality of racks for setting said tabulating mechanism, an analyzing mechanism also driven from said main driving shaft and adapted to operate said racks, a retracting bar disposed to travel in the paths of movement of said racks, a second shaft, levers mounted on 110 said second shaft and mounting said retracting bar, a rod connected to one end of one of said levers, a second rod operatively connected to be actuated by said main driving shaft, said first rod being disposed in the path of movement of said second rod and to be operated thereby, means for operating said first rod independently of said second rod when said driving shaft is at rest, and mechanism for resetting said tabulating mechanism independently of said analyzing mechanism when said racks have been so reset. 120

50. In an accounting machine, the combination with a main driving shaft, of a 130

tabulating mechanism driven by said main driving shaft and having a plurality of racks for setting said tabulating mechanism, an analyzing mechanism also driven from 5 said main driving shaft and adapted to operate said racks, a retracting bar disposed to travel in the paths of movement of said racks, a second shaft, levers mounted on said second shaft and mounting said re- 10 tracting bar, a rod connected to one end of one of said levers, a second rod operatively connected to be actuated by said main driving shaft, said first rod being disposed in the path of movement of said second rod 15 and to be operated thereby, and means for operating said first rod independently of said second rod when said driving shaft is at rest.

51. In an accounting machine, the combination with a main driving shaft, of a tabulating mechanism driven by said main driving shaft and having a plurality of racks for setting said tabulating mechanism, an analyzing mechanism also driven from 20 said main driving shaft and adapted to operate said racks, a retracting bar disposed to travel in the paths of movement of said racks, a second shaft, levers mounted on said second shaft and mounting said retract- 25 ing bar, a rod connected to one end of one of 30

said levers, a second rod operatively connected to be actuated by said main driving shaft, said first rod being disposed in the path of movement of said second rod to be operated thereby, and a plurality of resetting racks for resetting said tabulating mechanism, a bar disposed to travel in the path of movement of said resetting racks to retract them, levers mounting said bar, a rock-plate, a retracting lever, a link connecting said retracting lever to said rock-plate to actuate the same, said rock-plate being adapted to engage the levers of said retracting bar to retract the same when actuated by said retracting lever, a second 40 link, a bell-crank connecting said first rod with said second link, said second link connecting said bell-crank with said rock-plate so that the operation of said rock-plate will operate to retract the racks of said resetting 45 mechanism as well as the racks of said tabulating mechanism, the loose connection between said first and second rods permitting the operation of said first rod independently of said second rod.
